UNITED STATES PATENT OFFICE.

WILLIAM E. JOHNSON, OF DALE, TEXAS.

WIRES-STRETCHER.

1,209,148.

Specification of Letters Patent. Patented Dec. 19, 1916.

Application filed April 8, 1916. Serial No. 89,804.

To all whom it may concern:

Be it known that I, WILLIAM E. JOHNSON, a citizen of the United States, residing at Dale, in the county of Caldwell and State of Texas, have invented certain new and useful Improvements in Wire-Stretchers; and I do hereby declare the following to be a full, clear, and exact description of the invention, such as will enable others skilled in the art to which it appertains to make and use the same.

The invention relates to improvements in wire stretchers.

The object of the present invention is to improve the construction of wire stretchers and to provide a simple, practical and comparatively inexpensive wire stretcher capable of stretching line wires and woven wire and adapted to draw the same across the fence posts and hold the wires under tension while the wires are being stapled or otherwise secured to the posts without the provision of a separate anchoring post or other anchor.

25 A further object of the invention is to provide a wire stretcher of this character which will also be adapted for drawing the ends of a broken wire together and for holding the same while they are being spliced.

30 With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings Figure 1 is a perspective view of a wire stretcher constructed in accordance with this invention and shown in position for stretching woven fence wire.

45 Fig. 2 is an enlarged detail longitudinal sectional view illustrating the construction of the ratchet mechanism. Fig. 3 is an enlarged end elevation partly in section of the construction for mounting the wire stretcher on a fence post. Fig. 4 is a longitudinal sectional view of the same. Fig. 5 is an enlarged detail plan view of the rear end of the ratchet bar showing one of the wire clamps.

50 Like numerals of reference designate cor-

responding parts in the several figures of the drawings.

In the accompanying drawings in which is illustrated the preferred embodiment of the invention, 1 designates an operating lever 60 preferably constructed of metal and consisting of a single bar or piece of metal which is bent at one end on itself to form a loop 2 through which passes a ratchet bar 3 provided at one side with ratchet teeth 4 65 adapted to be engaged by a pawl 5 and a dog 6. The terminal 7 of the bar or piece of which the lever 1 is constructed is angularly bent and is riveted or otherwise secured to the body portion of the lever 70 at a point intermediate of the ends thereof. The pawl 5 is pivoted intermediate of its ends in the outer end of the loop 2 by a suitable pivot 8 and its front arm or portion engages the teeth of the 75 ratchet bar in advance of the lever, while its rear arm 10 extends back of the lever and constitutes an operating handle to enable the pawl to be readily operated manually to disengage it from the ratchet bar when it is 80 desired to move the operating lever 1 forwardly along the ratchet bar after an operation of the wire stretcher. The dog 6 is composed of two angle sides located at the upper and lower faces of the ratchet bar and 85 pivoted at their angles to links 9 which connect the pawl 6 with the lever, being pivoted to the latter at 11. The sides of the dog 6 are connected at their outer ends by a pin 12 or other suitable means which is adapted to 90 engage with the teeth of the ratchet bar. When the lever 1 is oscillated, the dog and the pawl will alternately engage the teeth of the ratchet bar and the lever will be advanced along the ratchet bar from the front 95 to the rear portion thereof to stretch a fence wire or wire fencing. In stretching woven fence wire or wire fencing, a clamp comprising a pair of vertical clamping bars 14 is employed, the clamping bars being secured in engagement with the wires by suitable bolts 15 arranged at intervals and piercing the clamping bars. The clamp is connected by converging links 16 with a chain 17 or other suitable flexible connection. The links 16 consist of rods provided at their ends with eyes and linked into eye bolts 18 at their outer ends and into a connecting ring 19 at their inner ends which ring is also detachably engaged by a hook 20 of the 110

chain 17. The chain 17 is also provided at its rear end with a hook 21 adapted to engage a perforation 22 of a connecting bar or link 23 which is pivoted at its rear end at 24 to the lever, the rear portion of the connecting bar being preferably bifurcated to straddle the lever as shown. The connecting bar also carries a wire clamp 26 consisting of a cam lever and a fixed jaw 27 to enable a single wire to be connected with the wire stretcher. The rear end of the ratchet bar is provided with a similar wire clamp 28 coacting with a rigid jaw 29 and adapted to engage a single wire, the two clamps being employed when the wire stretcher is used for drawing the ends of a broken wire together for enabling the same to be spliced.

The ratchet bar is equipped at its ends with rigid arms 30 having spaced parallel engaging portions 31 and inclined converging portions 32, the adjacent terminals of which are bent into parallelism and secured to the opposite faces of the front end of the ratchet bar. The arms 30 are preferably supported by a vertical brace 34 and the engaged portions 31 are provided with teeth 35 adapted to engage a post 36 at one side thereof, the other side of the post being engaged by a lever 37 preferably approximately L-shaped and pivoted at its angle at 38 between laterally projecting supporting arms 39 fixed to the upper and lower faces of the front end of the ratchet bar. The pivot 38 is removable and the supporting arms 39 are provided with a plurality of registering perforations 40 adapted to receive the pin or pivot 38 to enable the angle lever 37 to be arranged different distances from the ratchet bar for engaging posts of different sizes. The front engaging arm of the lever 37 is provided with a tooth 41 and the rear arm is connected by a pair of links 42 with an operating lever 43.

The rear arm of the post engaging lever 37 is provided with a plurality of perforations 44 which are adapted to receive the pivot 45 for connecting the links 42 adjustably to the post engaging lever to secure the desired gripping action and to enable the operating lever to be adjusted with relation to the post engaging lever when the latter is changed in its position on the laterally projecting arm 40 to suit the size of the post to be clamped.

The lever 43 is fulcrumed by a suitable pivot 46 between a pair of projecting plates 48 secured to and extending across the ratchet bar and provided at the toothed side thereof with curved extensions 49 which are adapted to form a guide for the chain 17. The lever 43 is also connected by a suitable pivot 46 to the rear end of the links 42 and it is adapted to be swung inwardly against the smooth edge of the ratchet bar to engage the lever 37 with the post. The lever 43 for operating

the post engaging means is adapted to extend through the loop of the operating lever 1 and it is retained in substantial alinement with the links by the operating lever 1 which prevents the lever 43 from swinging outwardly and releasing the wire stretcher from its engagement with the fence post.

When the post is gripped between the fixed arms 30 and the lever 37, the wire stretcher is securely mounted on the post in proper position for stretching a plurality of fence wires which may be drawn past the post and held while the fence wires or woven wire fencing is being stapled or otherwise secured to the post.

What is claimed is:—

1. A wire stretcher of the class described including a bar, rigid arms composed of spaced engaging portions provided with teeth for engaging a fence post at one side thereof, said arms being also provided with converging portions secured to the said bar at a point intermediate of the ends thereof, a brace located at one end of the bar and connecting the said arms, a pivoted lever carried by the bar and provided with means for engaging the opposite side of the post and means for operating the said lever.

2. A wire stretcher of the class described including a bar provided with fixed means for engaging one side of a fence post, laterally projecting supporting means extending from the bar, an angle lever fulcrumed intermediate of its ends on the said supporting means and provided at one of its arms with means for engaging the other side of the fence post and operating means connected with the other arm of the lever.

3. A wire stretcher of the class described including a bar provided with fixed means for engaging one side of a fence post, laterally projecting supporting means extending from the bar, an angle lever fulcrumed intermediate of its ends on the said supporting means and provided at one of its arms with means for engaging the other side of the fence post, an operating lever pivotally connected with the said bar, and a lever movable along the bar and having a loop receiving the said operating lever.

4. A wire stretcher of the class described including a ratchet bar provided with ratchet teeth, spaced rigid arms provided with teeth for engaging one side of a fence post and having converging portions secured to the ratchet bar between the ends thereof, a brace located at one end of the ratchet bar connecting the said arms, plates extending from the said bar, at the end thereof adjacent to the said brace, an angle lever pivotally mounted between the said plates and provided with front and rear arms, the front arm having means for engaging the other side of the fence post, an operating lever or member connected with the said lever at

rear arm thereof and means carried by the ratchet bar for securing the operating lever or member against movement and for co-acting with the ratchet bar for stretching a 5 wire.

5. A wire stretcher including a ratchet bar provided with fixed means for engaging one side of a fence post, an operating lever having a loop slidably arranged on the said bar 10 and carrying means for engaging the teeth thereof, an angle lever mounted at one side of the ratchet bar and having one of its arms

arranged to engage the other side of the fence post and an operating member connected with the other arm of the angle lever 15 and extending through the loop of the operating lever.

In testimony whereof I affix my signature in presence of two witnesses.

WILLIAM E. JOHNSON.
